UNITED STATES PATENT OFFICE

2,428,633

COMBING MACHINE FOR TEXTILE FIBERS

John William Nasmith, Heaton Mersey,
Manchester, EnglandApplication January 26, 1942, Serial No. 428,266
In Great Britain July 10, 1941Sections 3 and 10, Public Law 690, August 8, 1946.
Patent expires July 10, 1961

6 Claims. (Cl. 19—116)

1

In the art of combing textile fibres, combing machines of the rectilinear type have been and are being constructed in which the usual pair of nippers which grips a tuft of fibres as it is being combed has its swinging movement, to and from the detaching rollers, upon a point situated above the combing cylinder. This type of machine is first mentioned in the specification of British Letters Patent No. 132,987 granted to me, and after various methods of mounting the usual top comb in such a machine had been proposed and employed the mounting took the form at present industrially employed, of a frame oscillated about a pivot point and carrying arms to which the top comb is attached, projections on the arms sliding in grooves in the frame. The top comb fails to engage the fibre tuft being dealt with, and rises in disengagement therefrom, by contact with and release from a fixed member, as a result of the oscillatory movement. When the parts are accurately made and carefully machined, and assuming that the setting of the top comb is always carefully effected, this form works well. Any departure from these essentials, however, and ordinary wear, affect the working of the machine, as the top comb must of course slide freely and penetrate into the fibre tuft and then slidably withdraw therefrom at every "nip."

The chief object of the present invention is to provide a simple and efficient form of mounting for the top comb, and method of operation of the same, in which the sliding movement above described and its disadvantages and deficiencies are altogether eliminated. To achieve this, in a combing machine of the type referred to, the top comb is so mounted in a solid carrier member and controlled that in its reciprocatory movement it follows two different arcuate paths, along one of which it moves to a point of its penetration into and ultimate withdrawal from the fibre tuft, whilst between that point and the detaching rollers, when engaged in the tuft, it moves upon the other path. This is best attained by mounting the top comb carrier upon a pivotal point, with means for transferring it from that pivotal point to another as a result of its own reciprocation.

A further object of the present invention is to arrange the operating mechanism of the top comb in such a manner that the moment of penetration of the same into the fibre tuft at each reciprocation may be adjustably determined, and, arising from this, means can be provided for permitting such adjustment of the top combs of all the heads of a combing machine, simultaneously and to exactly the same degree.

2

These secondary objects are attained, firstly, by so mounting one of the two points of oscillation of the top comb that variation of point of contact of the top comb teeth with the fibre tuft, with ensuing penetration of said teeth into the latter, will occur at a point of the arc determined by the adjustment of the point of oscillation. Secondly by connecting together the mechanical members which are regulatable to vary this point of oscillation, in all the heads of the combing machine, to a common setting shaft, the simultaneous adjustment of all the points may be effected simply and without chance of error.

It may be desirable in some cases, in view of 15 the nature of fibres being treated, to cause the top comb to remain for a longer time in engagement with the fibre tuft, before its withdrawal from the same. That is to say, instead of making identical the point of penetration of the top comb

20 into the tuft and its point of subsequent withdrawal therefrom, the lift might be delayed to ensure thorough treatment of the fibres before the top comb leaves them. This may be simply effected in the present invention by giving the 25 setting shaft above referred to a slight rocking motion so that the transfer of the comb to the point of oscillation which causes withdrawal of the top comb teeth from the fibre tuft is correspondingly delayed, reverse rocking of the shaft for the next stroke bringing the said point of 30 oscillation to that for the penetration of the comb. In some cases greater control of the amount of waste fibre taken out in the combing can be exercised by this regulation of the times of penetration of the top comb into, and withdrawal 35 from, the fibre tuft.

Further, it is desirable, again having in mind the various kinds of fibre which may be subjected to combing, to vary the amplitude of throw of the top comb, in its oscillation to and from the detaching rollers. A device for this purpose may be suitably incorporated in a combing machine of the type referred to in the manner hereinafter described.

40 The invention embodying the means for carrying out the first above named object, with the combination of the other features above set forth, in a simple and compact form, will now be described with reference to Figure 1 of the annexed drawings, which shows the relevant parts in side elevation, parts being considered duplicated on the other side of the combing head where necessary. Figure 1a is a detail at right angles to the view of Figure 1, of a part of the mechanism. So 45 far as the top comb itself and its operative func-

tion in relation to the fibre combing, and the various parts of a combing machine of the type hereinbefore referred to, are concerned, these may be as usual, and further reference to them is deemed unnecessary.

Referring to the drawing Figure 1, the position of the usual combing cylinder is indicated at C and the lower roller of a detaching roller pair at D. The top comb 3 is carried by the top comb bridge 4 which is securely screwed upon a facing on the arm 5. The comb arm 5 and bridge 4 thus form a solid whole. Cast upon the arm 5 is the projection 6 tapped to receive the screw 7. The part 5a of the arm 5 is also tapped to receive the adjusting screw 9 with lock nut 10, the lower end of which screw rests, in the drawing, upon the bowl 11 fitted upon the pin 12 fixed in the machine framing, forming an open bearing. This pin 12 serves as the pivot point for the oscillation of the top comb when the latter is actually engaged in the fibre tuft.

Also pivoting upon the pin 12 is the arm 13 which carries the bowl 14—see also detail Figure 1a—and, as shown, this bowl is just below the screw 7. Thus, as the top comb oscillates above the centre 12, the arm 13 being held, the said screw will make contact with, and leave, the bowl. As the top comb 3 withdraws on its backward oscillatory movement from the detaching roller D, the rocking of the arm 5 upon its pivot 12 brings the screw 7 upon the bowl 14. A method of rocking the arm 5 with 5a will be later described. As the backward movement of the top comb continues, it will be clear that its pivotal centre is now transferred to the bowl 14 from the pivot pin 12, the screw 9 lifting from the bowl 11 as a result of the movement. Moving around this new pivotal centre the top comb lifts from the fibre tuft, and on the return oscillation it descends into and again engages the same. Continued movement then causes screw 7 to lift from the bowl 14 and the screw 9 to engage again with bowl 11, the pivotal point being thus again changed. Adjustment of the screw 9 determines the depth of penetration of the top comb teeth into the fibre tuft.

The path of the needles of the top comb in the movements is indicated in broken lines at A, and A'. When following the arc A the pivot point is pin 12 and the depth of penetration of the needles depends upon adjustment of the screw 9 as already stated. The arcuate path A' is followed when the bowl 14 constitutes the pivot point, and A'' indicates therefore the point of penetration and withdrawal from the fibre tuft of the top comb teeth. If the arm 13 and thus the bowl 14 were fixed, this point A'' would remain constant. The arm 13 is however connected to a further arm 15 upon the shaft 16 which is the setting shaft. By suitably controlling this shaft 16 from the headstock of the machine, the arm 13 at each head in the combing machine can be slightly moved around its pivot 12 to increase the distance between the bowl 14 carried by such arm and the screw 7. There is thus, when the top comb teeth have reached the point A'' on the backward movement, a small time lag as screw 7 is descending to make contact with bowl 14, so that the withdrawal of the top comb teeth from the fibre tuft is delayed to a point to the right of point A'' as viewed in the drawing. The arm 13 being restored to position by the return movement of the setting shaft 16 for the next stroke, the next penetration takes place at point A'' and so on. By ordinary adjustment means upon the

end of shaft 16 the position of all the arms 13 in the machine to regulate the moment of penetration can be altered simultaneously. Should it not be desirable to make independent the points of penetration into, and withdrawal of the top comb teeth from, the fibre tuft, the rocking of the setting shaft to produce the time lag above described may be omitted, the said shaft being still adjustable to adjust the point of penetration, which is thus made also the point of withdrawal, of the top comb.

In the Figure 1 is shown a means for variation of the throw or amplitude of oscillation of the top comb, conveniently incorporated in a machine head having the invention previously described applied to the top comb movement. The three-armed lever 17 is rocked by known means about the pivot 18 as usual, and has pivoted upon its upper arm at 19 the end of link 20 the other end of which bears a stud 21 which engages as shown in the arcuate slot 22 formed in the lever 23, to be adjusted in such slot as required and secured in adjusted position by a nut. The lever 23 is keyed upon a top comb shaft 24, and the lever 23, link 20, and lever 17 constitute the means for rocking such shaft to an extent which is regulated by the adjustment of the stud 21 in the arcuate slot 22 which is struck from centre 19. It follows from the latter that the drive may be adjusted without in any way affecting the position of the top comb 3 of any head of the machine during such adjustment. The amplitude of throw of the top comb will however be varied according to the distance to which the stud 21 is adjusted to or from the top comb shaft 24. Upon the shaft 24 is keyed the lever 28 to which is pivoted the end of the connecting rod 29 carrying the fork 30 which engages the pin 31 in the top comb arm 5. The adjustable drive is thus transmitted to the top comb.

I claim:

1. In a textile combing machine, a top comb and carrier therefor, forming a solid unit, such unit oscillating to and from the detaching roller position of the machine around a pivot point, and a secondary pivot to which the unit is transferred temporarily at each oscillation as the operative pivot point.
2. In a textile combing machine, a top comb and carrier therefor forming a solid unit, means for oscillating such unit around a pivot point in an arcuate path, a secondary pivot point with which the unit makes contact on oscillatory backward movement of the top comb, and an open bearing upon the unit engaging with and disengaging from the first pivot point.
3. In a textile combing machine, a unit consisting of top comb and carrier, a pivot upon which the unit is releasably held, means for oscillating such unit about such pivot, and a secondary pivot in the oscillatory path of such unit with which pivot the unit makes contact in the oscillation of the latter with resultant release of the same from the first pivot.
4. In a textile combing machine, a unit consisting of top comb and carrier, a pivot upon which the unit is releasably held, means for oscillating such unit around such pivot, and an adjustable secondary pivot in the oscillatory path of such unit with which at its adjusted point the unit makes contact in the oscillation of the latter with resultant release of the same from the first pivot.
5. In a textile combing machine having mechanism as claimed in claim 4, a pivoted arm which

bears the secondary pivot, and a rocked setting shaft connected with and imparting rocking motion to the arm and consequent movement of its borne pivot to and from the normal position of the latter, for the purpose hereinbefore set forth.

6. In a textile combing machine, the combination of a top comb and carrier therefor constituting a solid unit, two pivot points with which the said unit on oscillation makes alternate engagement with simultaneous release of contact with the other, a top comb shaft, a lever borne thereby, a connecting rod between the lever and the top comb carrier, a further lever upon the top comb shaft such lever having an arcuate slot therein, an oscillated driving lever, and a link pivoted thereto, the other end of such link engaging in the arcuate slot and being adjustable therein to and from the top comb shaft.
